UNITED STATES PATENT OFFICE.

ANTHONY W. LOSHBOUGH, OF DETROIT, MICHIGAN, ASSIGNOR TO STURGIS STEEL GO-CART COMPANY, OF STURGIS, MICHIGAN.

COLLAPSIBLE BABY-CARRIAGE.

948,070.

Specification of Letters Patent.

Patented Feb. 1, 1910.

Original application filed November 5, 1907, Serial No. 400,782. Divided and this application filed June 18, 1908. Serial No. 439,176.

To all whom it may concern:

Be it known that I, ANTHONY W. LOSHBOUGH, a citizen of the United States, residing at Detroit, Michigan, have invented certain new and useful Improvements in Collapsible Baby-Carriages, of which the following is a specification.

This invention relates to improvements in baby carriages.

10 It relates particularly to improvements in folding baby carriages, and is especially designed and adapted for use on the folding baby carriage shown in Letters Patent No. 866,145, issued September 17, 1907, to Otto 15 Kurz; and I have shown my improvements embodied in such a structure, although they are applicable for use in various other structures.

The main object of this invention is to 20 provide in a folding baby carriage, an improved brace for the wheel and means for automatically securing the parts in their erected position.

25 Further objects, and objects relating to structural details, will definitely appear from the detailed description to follow.

I accomplish the objects of my invention by the devices and means described in the following specification.

30 The invention is clearly defined and pointed out in the claims.

A structure embodying the features of my invention is clearly illustrated in the accompanying drawing, forming a part of this 35 specification, in which:

Figure 1 is a side elevation of a structure embodying the features of my invention, the wheels being removed and a portion of the handle broken away. Fig. 2 is a rear elevation, a portion of the handle being broken away. Fig. 3 is a side elevation of a structure embodying the features of my invention in its collapsed position, the wheel journals being broken away. Fig. 4 is an 40 enlarged detail section taken on a line corresponding to line 4—4 of Fig. 1, showing the detachable connection for the wheel braces to the wheel supports. Fig. 5 is a detail section showing the front support and 45 brackets for the seat.

50 In the drawing, the sectional views are taken looking in the direction of the little

arrows at the ends of the section lines, and similar numerals of reference refer to similar parts throughout the several views.

55

Referring to the drawing, 1 represents the running gear frame. The handle 2 is pivotally secured at the rear of the running gear frame by means of the pivots 3. On each of the side bars of the running gear frame are clip-like hangers 4 for the wheel supports 5. The wheel supports 5 are preferably formed of rods having downwardly-projecting wheel-carrying arms 6 with suitable journals, as 7, for the wheels. 65 The wheel supports are pivotally supported on the hangers, so that they are free to swing therein to permit the wheels to be folded upon each other under the running gear frame. The wheel supports 5 are provided with offsets forming crank-like arms 8, the offsets being preferably inclined downwardly toward the rear, as clearly appears from the drawing.

70

A pair of levers 9 is mounted on the side 75 bars of the running gear frame by means of the pivots 10, the pivots being located above the offsets or arms 8 of the wheel supports. The lower ends of the levers project downwardly below and preferably on the outside 80 of the arms 8 of the wheel supports, as clearly appears from the drawing. On the lower ends of the levers are loops 11 arranged to engage the arms 8, so that, when the levers are actuated, they serve to positively swing the wheel supports in and out to collapse or erect them. The levers 9 are 85 preferably connected to the handle 2 to be actuated thereby, by links 12, the links being adapted to serve as side-bars for the seat 90 13. These parts described are substantially the same as the corresponding parts of the patent hereinbefore referred to.

85

The wheel supports are locked and braced by means of the braces 14, pivoted on the 95 running gear frame at 15. These braces are preferably bail-like in form, their lower ends being connected by a suitable cross piece, as 16, which makes them more rigid and forms a very rigid brace for the wheel supports. 100

The arms 6 of the wheel supports are provided with fork-like clips 17, adapted to receive these braces when the wheel supports are in their erected or extended position.

The upper ends of the braces 14 are preferably curved rearwardly and downwardly beyond the pivots 15 thereof, and are connected by the links 18 to the wheel support actuating levers 9. These links are so arranged that, when the braces 14 are in position to engage the wheel supports, the pivot connections 19 for the links to the braces are thrown below the pivots 15 for the braces to the running gear frame, so that they serve as an effective lock for the levers, thus securely locking the carriage in its open or erected position, as well as bracing the wheel supports. The cross piece 16 of the braces is, as will be observed, at the rear of the carriage, so that it may be engaged by the foot of the operator to release the braces or push them into engaging position, thus forming a very effective and conveniently operated device.

20 The seat 13 is preferably supported at its forward end on the bracket 20, the same being preferably mounted on the pivot 10 for the levers 9. Extending across the running gear frame, toward the rear thereof, is a cross piece 21. This cross piece is preferably formed of sheet metal and serves as a brace for the running gear frame. The springs 22 for the seat 13 are preferably the spiral type and are mounted on the cross piece 21. This seat support is described in detail and claimed in my application filed concurrently herewith, the said application and this application being divisional cases of my application for Letters Patent filed November 5, 1907, Serial No. 400,782.

While I have illustrated the various parts in detail in the form preferred by me on account of the structural simplicity and convenience in manipulating the same, I am aware that my improvement is capable of being considerably varied in structural details without departing from my invention, and I desire to be understood as claiming the same specifically, as illustrated, as well as broadly.

Having, thus described my invention, what I claim as new and desire to secure by Letters Patent is:

1. In a collapsible carriage, the combination with the running gear frame, of a handle pivotally connected to said frame; wheels; wheel supports having arms thereon, pivotally secured to said frame; levers pivoted on said frame connected to said arms on said wheel supports for collapsing or erecting the same; links connecting the upper ends of said levers to said handle; a pair of braces pivoted on said frame; connecting links for said braces to said pivoted levers, the connecting pivots for said links to said braces being adapted to swing past the center of the brace pivots; a cross piece connecting the lower ends of said braces; and forked clips on said wheel supports adapted to receive said braces when the

parts are in their erected position, whereby said wheel supports are braced and the structure locked in its erected position.

2. In a collapsible carriage, the combination with the running gear frame, of a handle pivotally connected to said frame; wheels; wheel supports having arms thereon, pivotally secured to said frame; levers pivoted on said frame connected to said arms on said wheel supports for collapsing or erecting the same; links connecting the upper ends of said levers to said handle; a pair of braces pivoted on said frame; connecting links for said braces to said pivoted levers, the connecting pivots for said links to said braces being adapted to swing past the center of the brace pivots; and forked clips on said wheel supports adapted to receive said braces when the parts are in their erected position, whereby said wheel supports are braced and the structure locked in its erected position.

3. In a collapsible carriage, the combination with the running gear frame, of a handle pivotally connected to said frame; wheels; wheel supports having arms thereon, pivotally secured to said frame; levers pivoted on said frame connected to said arms on said wheel supports for collapsing or erecting the same; links connecting the upper ends of said levers to said handle; a pair of braces pivoted on said frame, adapted to be swung into engagement with said wheel supports; connecting links for said braces to said pivoted levers, the connecting pivots for said links to said braces being adapted to swing past the center of the brace pivots; and a cross piece connecting the lower ends of said braces, whereby said wheel supports are braced and the structure locked in its erected position.

4. In a collapsible carriage, the combination with the running gear frame, of a handle pivotally connected to said frame; wheels; wheel supports having arms thereon, pivotally secured to said frame; levers pivoted on said frame connected to said arms on said wheel supports for collapsing or erecting the same; links connecting the upper ends of said levers to said handle; a pair of braces pivoted on said frame, adapted to be swung into engagement with said wheel supports; and connecting links for said braces to said pivoted levers, the connecting pivots for said links to said braces being adapted to swing past the center of the brace pivots, whereby said wheel supports are braced and the structure locked in its erected position.

5. In a folding carriage, the combination with the running gear frame, of a handle pivotally connected to said frame; wheels; wheel supports pivotally secured to said frame; levers pivoted to said frame and connected to said wheel supports for collapsing

- or erecting the same; operating connections for said levers to the handle, whereby said levers are actuated to erect or collapse said wheel supports; a pivoted brace for said 5 wheel supports when in their erected position; and a link connection for said brace to said levers, the connecting pivots for said links to said brace being adapted to swing past the center of the brace pivots, whereby 10 the parts are locked in their erected position when said brace is in engagement with said wheel supports.
6. In a folding carriage, the combination with the running gear frame, of wheels; 15 wheel supports pivotally secured to said frame; a pair of levers; operating connections for said levers to said wheel supports, whereby said wheel supports are collapsed or erected; a pivoted brace for said wheel 20 supports; and connecting links therefor to said levers, the pivots for said links to said brace being adapted to swing past the center of the brace pivots whereby the carriage is locked in its erected position when said 25 brace is in engagement with said wheel supports.
7. In a folding carriage, the combination with the running gear frame, of wheels; wheel supports pivotally secured to said 30 frame; means for erecting and collapsing said wheel supports; a pivoted brace for said wheel supports; a connecting link for said brace to said wheel support actuating means whereby said brace is erected or collapsed, 35 the connecting pivot for said link to said brace being arranged to swing past the center of the brace pivot when the brace is in its engaging position, whereby the parts are locked in their erected position.
- 40 8. In a folding carriage, the combination with the running gear frame, of wheels; collapsible wheel supports; means for actuating said wheel supports for collapsing or erecting the same on the collapsing or erecting of the carriage; a locking toggle for said wheel support actuating means, one member of said toggle being arranged to serve as a brace for said wheel supports when the carriage is in its erected position.
9. In a folding carriage, the combination 45 with the running gear frame, of wheels; collapsible wheel supports; means for actuating said wheel supports for collapsing or erecting the same on the collapsing or erecting of the carriage; a locking toggle for said wheel support actuating means, one member of said toggle being arranged to serve as a brace for said wheel supports when the carriage is in its erected position.
10. In a folding carriage, the combination 50 with the running gear frame, of wheels; collapsible wheel supports; means for actuating said wheel supports for collapsing or erecting the same on the collapsing or erecting of the carriage; a brace for said wheel supports 55 pivoted on said running gear frame, the upper end of said brace being extended beyond its pivot and to the rear thereof; and a connecting link for the rearwardly extending end of said brace to said wheel collapsing or erecting means, the connecting pivot for said link to said brace being arranged to swing past the center of the brace pivot when the brace is in its engaging position, for the purpose specified.
- 55 In witness whereof, I have hereunto set my hand and seal in the presence of two witnesses.
